UNITED STATES PATENT OFFICE.

ALVA C. TERRELL, OF KANSAS CITY, MISSOURI.

DESIGN FOR A TIRE-TREAD.

57,745.

Specification for Design.

Patented Apr. 26, 1921.

Application filed October 11, 1920. Serial No. 416,322. Term of patent 14 years.

To all whom it may concern:

Be it known that I, ALVA C. TERRELL, a citizen of the United States, residing at Kansas City, in the county of Jackson and State of Missouri, have invented a new, original, and ornamental Design for Tire-Treads, of which the following is a specification, reference being had to the accompanying drawing, forming a part thereof, in which—

Figure 1 is a fragmentary elevation of my new design.

Fig. 2 is a cross section taken on line II—II of Fig. 1 of the design.

I claim:

The ornamental design for a tire tread, as shown.

ALVA C. TERRELL.
